COMBINED SOAP DISPENSER, TOWEL DISPENSER AND MIRROR

Joseph C. Grasso, New York, and Patrick Grasso, Scarsdale, N.Y., assignors to Accessory Specialties, Inc., Long Island City, N.Y., a corporation of New York

Filed Dec. 23, 1965, Ser. No. 311

Term of patent 14 years

(Cl. D4—3)

Fig. 1

Fig. 2

Fig. 3

Fig. 5

FIG. 1 is a front perspective view of a wall-mounted combined soap dispenser, towel dispenser and mirror embodying our new design;

FIG. 2 is a front view thereof;

FIG. 3 is a left side view thereof, the right side view (not shown) being a mirror image thereof;

FIG. 4 is a top plan view thereof; and

FIG. 5 is a bottom view thereof.

The wall surface shown in broken lines in FIGS. 3—5 is included for illustrative purposes only.

We claim:

The ornamental design for a combined soap dispenser, towel dispenser and mirror, as shown and described.
